COMBINED KEY CHAIN AND ARTICLE HOLDER

Marie B. Bush, 5701 Haines Road, St. Petersburg,
Fla., assignor of one-half to Lee E. Arnold, St.
Petersburg, Fla.

Filed Apr. 19, 1963, Ser. No. 74,525

Term of patent 14 years

(Cl. D17—14)

Fig. 1

Fig. 2

Fig. 3

Fig. 4

FIGURE 3 is a perspective view thereof on a reduced scale and showing the article in an open position;

I claim:

The ornamental design for a combined key chain and article holder, as shown.
